UNITED STATES PATENT OFFICE.

THOMAS S. PATTERSON, OF FLUSHING, NEW YORK.

CENTRIFUGAL SEPARATOR.

SPECIFICATION forming part of Letters Patent No. 731,215, dated June 16, 1903.

Application filed May 9, 1902. Renewed May 6, 1903. Serial No. 155,944. (No model.)

To all whom it may concern:

Be it known that I, THOMAS S. PATTERSON, of Flushing, county of Queens, New York, have invented certain new and useful Improvements in Centrifugal Separators, of which the following is a clear, full, and exact description.

This invention refers to a centrifugal separator designed to throw off the liquid matter contained in fibrous material or extract the oils from greasy fabrics, and is adapted especially for those materials containing liquids that become more liquefied on the application of heat, whereby the extraction becomes easier.

This machine is constructed more particularly for the extraction of greases or oil from waste or light materials in which the rotating separator is driven by steam, the exhaust being adapted to heat the material to be deprived of the oil or grease, making the grease more easy to throw off.

A further object is to provide a separator that is cheaply and simply constructed and in which the revolving sustaining parts are well lubricated by a portion of the oil extracted and a machine in which no packing is necessary.

With these ends in view I have devised the construction described hereinafter and illustrated in the accompanying drawings, in which—

Figure 1 is a central vertical section of the machine. Fig. 2 is a section on line 2 in Fig. 35 1, and Fig. 3 is a detail view of jet and blades of a turbine used to revolve the extractor.

In the views, 10 is a standard of suitable shape provided in the bottom with a disk 11, screwed thereto, and another disk 12, both being supplied with a ball-retainer for the balls 13, the whole forming a thrust-bearing with a stem 14 projecting therefrom, in which a groove 15 receives the tongue 16 of the shaft 17, which locks thereon and is adapted to revolve therewith. A circular table portion 18 on the standard 10 and a raised portion 19 thereon supports the boss or abutment 20, secured to a plate or disk 21. A series of blades 22 are secured to the disk 21 to receive the impact of the steam from a jet 23, and a

curved set of blades 24 are arranged on the outside of said driving-blades, extending to the peripheral flange 25 and, being covered with a plate 26, form the chambers 27, (shown more particularly in Fig. 2,) the plate 26 being removed in this figure. A perforation 28 leads from each of these chambers 27 into the dome 29, which is secured to the plate 21 and revolves therewith and has a series of blades 30, adapted to draw and force the contents of the dome toward the outlet-pipe 31. Outside the dome and secured to the periphery of the revolving portion is a screen 32, supported in any suitable manner, but illustrated as being sustained by the standards 33 and a ring 34. This screen and the dome form the chamber for receiving the fibrous materials from which the liquid matter is to be extracted. A casing 35 on the table portion 18 serves to receive the oil thrown off by the rotation of the screen, and a pipe 36 carries off the oil or grease so received.

When the machine is operated, the jet 23 ejects a stream that, striking the blades 22, (see Fig. 3,) causes the plate 21 and the parts supported thereon to revolve and the blades 24 acting to propel the steam thrown back by the blades 22 through the compartment 27 and perforation 28 into the dome 29, which is heated by said steam. A set of blades 30 act to keep the steam in circulation through the dome and passes it to and through the outlet-pipe 31. It will thus be evident that any material of an oily nature or a fibrous greasy mass—as, for instance, oil-soaked waste—that is introduced into the chamber formed by the dome 29 and the screen 32 is heated, making the oil more liquefied, and the revolving of the holder centrifugally separates it from the waste, and, the casing 35 receiving it, it flows to the flat table portion 18. A duct 19^a serves to lead the oil to the moving parts of the machine, insuring their lubrication, and the pipe 36 being raised so as to place its inlet higher than the duct 19^a the machine is lubricated before the surplus flows off through the pipe 36. This construction of the separator needs no packing and is economical in its working, the steam supplying the motive power and also serving to

heat the dome to assist in the liquefaction of the oil or grease, and thereby hasten and facilitate its extraction.

The exact construction as shown of the 5 supporting structure is not essential, as any suitable construction would suffice. Likewise any desirable mesh of screen may be employed from a wire to a cloth strip to filter or purify the extracted grease or oil, or a cloth 10 can be attached and used in addition to the wire screen.

Having thus described my invention, what I claim as new, and desire to secure by Letters Patent, is—

15 1. A centrifugal separator comprising a rotary steam-driven drum, and an inclosed chamber arranged within the drum so as to heat the contents thereof, said chamber being constructed to receive the exhaust-steam.

20 2. A centrifugal separator comprising a steam-driven drum, said drum containing a heating-chamber to receive the exhaust-steam, and blades in said chamber to eject the steam.

25 3. A centrifugal separator comprising a steam-driven turbine, a drum supported and carried by the turbine, and an inclosed heating-chamber within the drum receiving the exhaust from the turbine.

30 4. A centrifugal separator comprising a steam-driven turbine, a drum supported on and carried by the turbine, a heating-chamber within the drum said chamber receiving the exhaust from the turbine, and means in the chamber for ejecting the steam.

35 5. A centrifugal separator comprising a steam-driven turbine supporting a perforated drum, said drum containing a heating-chamber to receive the exhaust-steam, and ducts leading from the spaces between the turbine- 40 blades to said chamber.

45 6. A centrifugal separator comprising a steam-driven turbine, supporting a perforated drum, said drum containing a heating-chamber to receive the exhaust-steam, and ducts leading from the spaces between the turbine-blades to said chamber, and blades in said chamber to eject the steam.

50 7. A centrifugal separator comprising a standard, a casing thereon, a revolving steam-turbine in said casing supporting a perforated drum, said drum containing a heating-chamber to receive the exhaust-steam, an outlet-pipe for said casing, and an outlet-pipe for said chamber.

55 8. A centrifugal separator comprising a standard, a casing thereon, a revolving steam-turbine supporting a perforated drum, said

drum containing a heating-chamber, a series of blades in said chamber, and an outlet for said casing.

60 9. A centrifugal separator comprising a standard, a casing thereon, a revolving steam-driven turbine supporting a perforated drum, ducts communicating from the space adjacent to each blade to a heating-chamber in said 65 drum.

10. A centrifugal separator comprising a standard, a casing thereon, a revolving steam-driven turbine supporting a perforated drum, a duct communicating from the space adjacent to each blade of said turbine to a heating-chamber in said drum to eject the steam.

70 11. A centrifugal separator comprising a standard, a casing thereon, a supporting-bearing in said standard to receive a removable shaft revolving with a steam-turbine, a perforated drum on said turbine, a duct communicating from said turbine to a heating-chamber in said drum, and an outlet-pipe for said casing.

75 12. A centrifugal separator comprising a standard, a casing thereon, a supporting-bearing in said standard to receive a movable shaft, said shaft revolving with a steam-turbine, a set of auxiliary blades to convey the steam to a heating-chamber through perforations in said turbine, a perforated drum inclosing said chamber, blades in said chamber to eject the steam therefrom, and an outlet-pipe from said casing.

80 13. A centrifugal separator comprising a steam-driven turbine supporting a drum, a stationary casing around said drum, lubricating-ducts communicating from said casing to the bearings of the machine, and an outlet-pipe leading from said casing with its inlet end above the lubricating-ducts to insure the lubrication of the machine.

85 14. A centrifugal separator comprising a steam-driven turbine supporting a drum, a heating-chamber in said drum to receive the exhaust-steam, a casing around said drum, lubricating-ducts to convey the extracted materials to the bearings of the machine, and an outlet-pipe leading from said casing with its inlet end above said lubricating-ducts to insure the lubrication of the machine.

90 In testimony whereof I have signed my name to this specification in the presence of two subscribing witnesses.

THOMAS S. PATTERSON.
